Primary Examiner — George D. Kirschbaum*Assistant Examiner* — Kathleen L Jones(74) *Attorney, Agent, or Firm* — Birch, Stewart, Kolasch & Birch, LLP(57) **CLAIM**

The ornamental design for a display screen with graphical user interface, as shown and described.

DESCRIPTION

1. Display screen with graphical user interface

1.1 : Front

The attached Appendix includes a reference view relating to the present design, and is expressly incorporated into the present application by reference thereto.

The broken lines depict portions of the display screen with graphical user interface that form no part of the claimed design.

1 Claim, 1 Drawing Sheet(56)
